US0D1034465S

(12) **United States Design Patent** (10) **Patent No.:** **US D1,034,465 S**
(45) **Date of Patent:** **** Jul. 9, 2024**

(54) **CONNECTOR**

- (71) Applicant: **Molex, LLC**, Lisle, IL (US)
(72) Inventors: **Ravikanth Desai**, Bengaluru (IN);
Rahul Bhaskar, Bengaluru (IN);
Narayan Mithun, Bengaluru (IN);
Kalidindi Ramesh Raju, Bengaluru (IN);
Debashis Sarkar, Bengaluru (IN)
(73) Assignee: **Molex, LLC**, Lisle, IL (US)
(**) Term: **15 Years**
(21) Appl. No.: **29/753,387**
(22) Filed: **Sep. 30, 2020**
(51) **LOC (14) Cl.** 13-03
(52) **U.S. Cl.**
USPC **D13/133**; D13/153; D13/156; D13/147
(58) **Field of Classification Search**

Assistant Examiner — Bryan N. Melvin

(57) **CLAIM**

The ornamental design for a connector, as shown and described.

DESCRIPTION

FIG. 1 is a rear top perspective view of a connector showing our new design;

FIG. 2 is a front top perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a rear view thereof;

FIG. 9 is a rear top perspective view of a connector in an alternative embodiment;

FIG. 10 is a front top perspective view thereof;

FIG. 11 is a left side view thereof;

FIG. 12 is a right side view thereof;

FIG. 13 is a top view thereof;

FIG. 14 is a bottom view thereof;

FIG. 15 is a front view thereof; and,

FIG. 16 is a rear view thereof.

The broken lines immediately adjacent to the shaded area represent the bounds of the claimed design and form no part thereof. The broken lines depicting the remainder of the connector form no part of the claimed design.

1 Claim, 16 Drawing Sheets
